UNITED STATES PATENT OFFICE

2,532,112

CHECKER FOR FURNACES

Fred H. Mackensen, Bettendorf, Iowa, assignor
to Mexico Refractories Company, Mexico, Mo.,
a corporation of Missouri

Application December 16, 1944, Serial No. 568,431

6 Claims. (Cl. 263—51)

1

The present invention relates to high temperature furnace construction and particularly to the regenerating chambers of heating furnaces wherein a checker arrangement of heat absorbing units is made for the purpose of utilizing the heat of the waste gases as they pass from the heating chamber to the stack or chimney. Such devices have been the subject matter of considerable development as witnessed by the following Letters Patent; Bigelow No. 1,916,458, McKelby No. 2,107,675, Milner No. 2,257,392, wherein the structural features of the checker chamber are stressed. In other Letters Patent such as No. 2,108,871 and No. 2,303,741 stress is placed upon the cleaning of checkers.

It is the purpose of my invention to provide a new type of checker unit whereby the checker construction is practically self-cleaning so that it is not necessary to clean or disturb the checkers during a campaign in order to maintain their efficiency at a high level.

It is a further purpose of my invention to provide individual checker units of such a nature that they can be arranged in piers in the checker chamber in such relation to each other as to disperse the air and gas to all parts of the chamber thus obtaining uniform temperatures and providing more heating area per cubic foot of chamber volume. The particular layout of the piers of checker units will, of course, vary because of the great variety of different designs of furnaces and sizes of chambers. However, the fundamental design of the refractory units which comprise the checker elements that make up the piers, makes it possible to individually vary the construction without varying the individual design of the checker unit and without losing any of the advantages thereof.

The nature and advantages of my invention will appear more fully from the following description and the accompanying drawings wherein a preferred form of the invention is shown. It is to be understood however, that the drawings and description are illustrative only and are not to be taken as limiting the invention, except insofar as it is limited by the claims.

In the drawings:

Figure 1 is a vertical sectional view transversely through a portion of a check chamber in a regenerator open hearth furnace;

2

Figure 2 is a sectional view taken at right angles to Figure 1;

Figure 3 is a longitudinal sectional view through a preferred form of checker unit employed in accordance with my invention;

Figure 4 is a plan view of the unit;

Figure 5 is a longitudinal sectional view through a top unit employed in building the piers of checker units;

Figure 6 is a plan view of a slightly different form of checker unit wherein the unit is made up of segments;

Figure 7 is a view in side elevation of the checker unit shown in Figure 6; and

Figure 8 is a plan view of one of the segments of the unit shown in Figure 6.

In checker chambers of regenerator furnaces, the waste gases are circulated from the heating chamber in one direction to heat the refractory elements in the checker chamber for a certain length of time, and then the air flow is reversed so that heated refractories give up their heat to the air going into the heating chamber. This means that waste gases may carry with them particles in suspension, condensable vapors and even large particles so that the horizontally extending surfaces in the checker chamber, and any surfaces in the checker chamber that form substantial pockets with a supporting surface more nearly horizontal or as nearly horizontal as the angle of repose of the particles, will collect the particles.

According to my invention I propose to provide a checker brick which, because of its shape, I refer to as an hour glass unit. In the drawings a unit of this character is shown in cross section at 10, Figure 3. Both ends 11 and 12 of the unit are larger in internal and external diameter than the mid portion 13 of the unit. The unit is made of a suitable refractory material for use in open hearth furnace checker chambers. This unit has flat top and bottom surfaces which are substantially parallel to each other so that several of the units 10 may be stacked one upon the other in the manner shown in Figure 1 of the drawings. The several units stacked one upon the other may extend from supporting rows 14 of fire brick at the bottom of the checker chamber upwardly to a short distance below the roof 15 of the checker chamber. In many open hearth

furnaces there is a direct passage upward through the roof 15 and horizontally to the heating chamber. There is usually a supporting means in the horizontal portion of this passage for a burner to supply the heat in the heating chamber of the furnace. The burner receives its air for combustion from the checker chamber, the air entering the checker chamber at the bottom inlet 16 (see Figure 2) and passing upward between supporting arches 17 and the rows of brick 14 between piers 18 of the checker units 10. The checker units are carried on the brick 14 in such fashion that they are open at the lower ends. The effect of these piers of checker units is to provide a multiplicity of channels in the checker chamber, some of the channels being inside the units and other channels being between the units. The piers may be spaced and staggered in any suitable form to provide for the best distribution of the air channels in the checker chamber. It is immaterial whether the gas passing through the chamber is going up or down, insofar as obtaining a thorough contact of the gas with the refractory checker units is concerned. The particular hour glass shape of the individual checker units provides alternate surfaces vertically through the checker chamber against which the gas is directed. Inside the piers there are alternate restrictions and expansions in cross section of the passages. This is likewise true outside the piers but the restrictions are at the level where the greatest cross section inside the piers exists. The angle made by the surfaces of the checker units 10 with a horizontal line is much greater than the angle of repose for any particles that are carried over from the heating chamber. If vapors condense and form deposits, the air circulation around the piers and through the piers tends to remove any accumulation of material at a particular point on a unit. The several checker units stacked one upon the other may, of course, be cemented together as desired. Units are molded quite smooth and are matched carefully in mounting one on top the other so as to leave no ledges projecting to invite the accumulation of foreign particles. Referring now to Figure 5 of the drawings, this figure illustrates a top checker unit 10a. This checker unit is essentially the same as that shown in Figures 3 and 4 of the drawings except that it has its upper edge 19 tapered as shown so as to prevent the accumulation of particles at the top edge of the unit.

It may be desirable from a molding standpoint to make the checker units in more than one piece. Figures 6, 7 and 8 illustrate a checker unit which is made up of four pieces. An individual piece 20 is shown in Figure 8 as being semicircular in cross section and tapering from one end to the other so as to provide surfaces 21 and 22 of the right contour. Four of these pieces 20 are then cemented together or otherwise connected so that they provide a complete unit 23 wherein the joints 24 between horizontal adjacent units are staggered circumferentially of the assembly. The vertical faces of the units 20 are of such shape that they can be provided with tongue and grooved elements to facilitate uniting the individual pieces 20 into a complete checker unit.

I find that a checker chamber constructed with piers made with the checker unit disclosed herein has the distinct advantage that it is self-cleaning so that it is not necessary to clean the checker unit during a campaign. Since there is no cleaning done, I have no difficulty with the checker

units being pushed out of place or falling. The whole construction of the checker unit provides for a high efficiency of the refractories since I obtain a maximum heating area per cubic foot of chamber volume. For example, I can provide an effective heating surface of approximately three square feet of heat for each cubic foot of chamber volume.

It is believed that the foregoing description will enable those skilled in this art to understand and practice the invention disclosed herein. Having thus described my invention, I claim:

1. A checker installation for regenerative furnaces comprising a supporting structure, and hollow annular piers of refractory material resting on said structure and spaced from each other and open at both ends, thereby providing air passages through the piers and between them, the piers comprising sections increasing in cross sectional area alternated with sections decreasing in cross sectional area, the surfaces where the directions change being curved in the direction corresponding to the length of the piers.

2. A checker installation for regenerative furnaces comprising a supporting structure, and hollow annular piers of refractory material resting on said structure and spaced from each other and open at both ends, thereby providing air passages through the piers and between them, the piers comprising sections increasing in cross sectional area alternated with sections decreasing in cross sectional area, the slope of the surfaces in both sections being so small as substantially to prevent accumulation of fine particles carried by waste gases into said air passages, the surfaces where the directions change being curved in the direction corresponding to the length of the piers.

3. A checker installation for regenerative furnaces comprising a supporting structure, and hollow annular piers of refractory material resting on said structure and spaced from each other and open at both ends, thereby providing air passages through the piers and between them, the piers comprising sections increasing in cross sectional area alternated with sections decreasing in cross sectional area, the slope of the surfaces in both sections being so small as substantially to prevent accumulation of fine particles carried by waste gases into said air passages, the top and bottom ends of said piers being at the points of greatest cross sectional area, the surfaces where the directions change being curved in the direction corresponding to the length of the piers.

4. A checker unit of refractory material comprising a hollow body with its opposite ends substantially equal in shape and size so that units may be stacked, said body gradually decreasing in cross section from its ends toward the center, said body being composed of a pair of like sections tapering from end to end, the small ends of the two sections being joined.

5. A checker unit of refractory material comprising a hollow body with its opposite ends substantially equal in shape and size so that units may be stacked, said body gradually decreasing in cross section from its ends toward the center, said body being composed of a pair of like sections tapering from end to end, the small ends of the two sections being joined, said sections each comprising two semiannular like pieces, joined together, the longitudinal joints between pieces of one section being staggered with respect to longitudinal joints in the adjacent sections.

6. A checker unit of refractory material for the top of a pier of a regenerative furnace comprising a hollow circular body having its major portions substantially symmetrical about vertical and horizontal axes, said body gradually decreasing in cross section from its ends to its center, the bottom face of said body being flat to permit stacking on the top of a column, the upper edge of said body being tapered to an edge to prevent accumulation of particles at the top edge of said unit.

FRED H. MACKENSEN.
